UNITED STATES PATENT OFFICE.

THOMAS C. SHEEHAN, OF UPPER MONTCLAIR, NEW JERSEY, ASSIGNOR TO WADE & BUTCHER CORPORATION, A CORPORATION OF NEW JERSEY.

METHOD OF MAKING KNIFE BLADES, ETC.

Application filed June 4, 1924. Serial No. 717,792.

To all whom it may concern:

Be it known that I, THOMAS C. SHEEHAN, a citizen of the United States, residing at Upper Montclair, county of Essex, and

5 State of New Jersey, have invented a new and useful Improvement in Methods of Making Knife Blades, etc., of which the following is a specification.

This invention relates to a method of making elongated articles having relatively thick and thin edges, such for example as the blades of table knives.

In rolling articles having relatively thick and thin edges, the thin edge offers less resistance to elongation than the thick edge, and so the thin edge stretches more than the thick edge. This differential elongation results in a product which is not straight but laterally curved, the thick edge having the 20 shorter radius. Heretofore, it has been necessary to subject such curved articles to a number of rerolling operations in order to gradually reduce them to straight form before they could be sent to the finishing devices or machines.

It has been discovered that the necessity for these article straightening operations can be avoided by forming, from a blank, a slug of the required width and having relatively thick and thin edges with excess metal adjacent its thick edge, and then longitudinally rolling said slug to generally lengthen the same and to crowd said excess metal along with the thick edge to lengthen the latter in compensation for the natural differential elongation of said thick and thin edges during the rolling operation, thus producing a straight product without rerolling operations and the additional cost incident thereto.

It has also been discovered that by rolling transverse ridges on the slug as it is formed by rolling dies having corresponding transverse depressions, the material is retarded and caused to spread laterally more than it does longitudinally.

The main object of the present invention is the production of a method of making table knife blades or other elongated articles 50 having relatively thick and thin edges, in which method one or both of these discoveries are utilized in the interest of greater economy in production and improved quality of product. With this and other objects not specifically mentioned in view, the in-

vention consists in certain acts or steps which will be hereinafter fully described and then specifically set forth in the claims hereunto appended.

In the accompanying drawings, which form a part of this specification and in which like characters of reference indicate the same or like parts, Fig. 1 is a perspective view of a blank of steel from which a table knife blade is to be made; Fig. 2 is a perspective view of a slug forged from the blank shown in Fig. 1 in one operation; Fig. 3 is a cross-sectional view taken on the line 3—3 in Fig. 2; Fig. 4 is a perspective view of a knife blade rolled from the slug shown in Fig. 2; Fig. 5 is a cross-sectional view taken on the line 5—5 in Fig. 4; Fig. 6 is a perspective view diagrammatically showing the rolls of a rolling mill with segmental rolling dies operating to convert a blank, 75 as in Fig. 1, into a slug, as in Fig. 2; Fig. 7 is a perspective view, on an enlarged scale, of one of a pair of segmental rolling dies adapted to produce the slug shown in Fig. 2; and Fig. 8 is a perspective view, on an 80 enlarged scale, of one of a pair of rolling dies for converting the slug of Fig. 2 into the knife blade of Fig. 4.

In carrying the invention into effect, a blank 9, cut from a rod of steel, is heated 85 and forged to form a slug 10. This may be done either by the use of a drop hammer and suitable stamping dies, or by the use of a rolling mill with suitable rolling dies. The method in its preferred form contemplates the use of a rolling mill and suitable rolling dies both for making the slug and for transforming the slug into the knife blade, for reasons which will hereinafter appear.

When the slug 10 is to be rolled from the blank 9, the latter is passed between two segmental rolling dies 11—11 secured, in a well known manner not shown, to the rolls 12—12 of a rolling mill, the construction 90 and operation of which is well known and needs no description herein.

Each die 11 is provided with an elongated depression 13, the purpose of which is to provide an excess of metal at 14 on either 105 side of the slug 10 adjacent its thick edge, the excess metal extending along said edge and varying in quantity at different points in accordance with the double taper of the blade to be produced and the consequent 110

progressive change in the differential elongation of the blade as it is rolled from the slug. Each die 11 is further provided with a series of transverse depressions 15. These 5 depressions serve to form transverse ridges 16 on the slug as it is being rolled in the mill. The effect of these transverse depressions in the dies and ridges on the slug is to retard the flow of metal and cause it to 10 spread laterally more than it does longitudinally. In this way, the major portion of the blank is spread to the width of the blade during the initial rolling operation.

After the slug has been made, it is passed 15 between a pair of segmental rolling dies 17 mounted on mill rolls like those carrying the dies 11—11. During the second pass; that is, between the dies 17—17, the slug is but slightly increased in width but greatly 20 increased in length, and of course reduced in thickness to the desired degree. If there were no excess metal at 14 on the slug passed between the dies 17—17, the differential elongation of the thick and thin edges of 25 the slug rolled thinner by the dies 17—17 would result in a product which is laterally curved, the thick edge being of the shorter radius. When, however, there is excess metal adjacent or along the thick edge of 30 the slug, this excess metal is crowded along with the thick edge of the slug and builds onto or lengthens the thick edge in compensation for the natural differential elongation of the thick and thin edges.

35 The differential elongation of the thick and thin edges being compensated for by just enough metal at the thick edge to lengthen it to the same extent that the thin edge is lengthened, the blade 18 rolls out 40 straight, as shown in Fig. 4, and ready for the succeeding trimming, grinding and polishing operations. By this method, the number of operations necessary to transform a blank into a knife blade is reduced to two, 45 and the metal, first spread transversely in the slug 10, and then elongated in the knife blade 18, is given a degree of density, hardness and grain which greatly facilitates the 50 grinding and polishing operations which follow.

It is to be understood that the method is applicable to the manufacture of articles other than knife blades and of materials other than steel.

55 What is claimed is:

1. The method of making an elongated article having relatively thick and thin edges, which consists in forming from a blank a slug of the required width and having relatively thick and thin edges with excess material adjacent its thick edge, and then longitudinally rolling said slug to generally lengthen the same and to crowd said excess material along with said thick edge 60 to lengthen the latter in compensation for 65

the natural differential elongation of said thick and thin edges.

2. The method of making an elongated article having relatively thick and thin edges, which consists in forming from a blank a slug of the required width and having relatively thick and thin edges with excess material distributed in varying quantity along and adjacent said thick edge, and then longitudinally rolling said slug to generally lengthen the same and to crowd said excess material along with said thick edge to lengthen the latter in compensation for the natural differential elongation of 70 said thick and thin edges.

3. The method of making an elongated article having relatively thick and thin edges, which consists in forging from a blank a slug of the required width and having relatively thick and thin edges with excess material adjacent its thick edge, and then longitudinally rolling said slug to generally lengthen the same and to crowd said excess material along with said thick edge to lengthen the latter in compensation for the natural differential elongation of 80 said thick and thin edges.

4. The method of making an elongated article having relatively thick and thin edges, which consists in longitudinally rolling from a blank a slug of the required width and having relatively thick and thin edges with excess material adjacent its thick edge, and then longitudinally rolling said slug to generally lengthen the same and to crowd said excess material along with said thick edge to lengthen the latter in compensation for the natural differential elongation of 90 said thick and thin edges.

5. The method of making an elongated article having relatively thick and thin edges, which consists in longitudinally rolling from a blank a slug having a series of transverse ridges for retarding and spreading the material to the required width and also having relatively thick and thin edges with excess material adjacent its thick edge, and then longitudinally rolling said slug to generally lengthen the same and to crowd said excess material along with said thick edge to lengthen the latter in compensation for the natural differential elongation of 100 said thick and thin edges.

6. The method of making an elongated article having relatively thick and thin edges, which consists in forming from a blank a slug of the required width and having relatively thick and thin edges with excess material adjacent its thick edge, and then passing said slug between rolling dies to generally lengthen the same and to crowd said excess material along with said thick edge to lengthen the latter in compensation for the natural differential elongation of 110 said thick and thin edges.

7. The method of making an elongated article having relatively thick and thin edges, which consists in passing a blank between rolling dies for forming a slug of the required width therefrom and having relatively thick and thin edges said dies being provided with elongated depressions for forming up excess material adjacent the thick edge of the slug, and then longitudinally rolling said slug to generally lengthen the same and to crowd said excess material along with said thick edge to lengthen the latter in compensation for the natural differential elongation of said thick and thin edges.
8. The method of making an elongated article having relatively thick and thin edges, which consists in passing a blank between rolling dies for forming therefrom a slug having relatively thick and thin edges said dies having transverse depressions for rolling transverse ridges on said slug and retarding and spreading the material to the required width and also having elongated depressions for forming up excess material adjacent the thick edge of said slug, and then longitudinally rolling said slug to generally lengthen the same and to crowd said excess material along with said thick edge to lengthen the latter in compensation for the natural differential elongation of said thick and thin edges.
9. The method of making an elongated article having relatively thick and thin edges, which consists in passing a blank between rolling dies for forming therefrom a slug having relatively thick and thin edges said dies having transverse depressions for rolling transverse ridges on said slug and retarding and spreading the material to the required width, and then longitudinally rolling said slug to lengthen the same.
